H. SEGUCHI
MEANS FOR BEATING OF BAGASSE FOR THE IMBIBITION
OF SAME IN CANE SUGAR MAKING INDUSTRY
Filed July 20, 1926

FIG. 1.

H. Seguchi
inventor

By: Marks & Clark
A. A. M.

UNITED STATES PATENT OFFICE.

HIROMU SEGUCHI, OF HORIZAI, TAICHU-SHU, TAIWAN, JAPAN.

MEANS FOR BEATING OF BAGASSE FOR THE IMBIBITION OF SAME IN CANE-SUGAR-MAKING INDUSTRY.

Application filed July 20, 1928, Serial No. 123,765, and in Japan March 18, 1926.

My invention relates to improvements in means for beating bagasse between two adjacent series of milling rollers for the purpose of thoroughly saturating the bagasse.

5 The principal object of this invention is to break and beat the compact mass of bagasse as it is conveyed from one series of milling rollers to the next series of milling rollers by means of apparatus designed to maintain 10 a uniform and complete mixing of the upper, middle and lower parts of the layer of compressed bagasse with each other, and at the same time a thorough and even sprinkling of water on all parts of the bagasse 15 to ultimately effect a high degree of juice extraction.

Other objects as well as the nature, characteristic features and scope of the invention will be more readily apparent from the following description taken in connection with 20 the drawings.

In the accompanying drawings Fig. 1 is a vertical sectional view of an embodiment of the apparatus according to this invention applied on the bagasse conveyor between two adjacent series of crushing rollers. Fig. 2 is a front view of the rotatable beater which is designed to beat the bagasse during the sprinkling thereof.

30 Heretofore it has been difficult to maintain a uniform and complete mixing of the upper, middle and lower parts of a layer of bagasse with each other, as bagasse once crushed and extracted of juice by any one series of crushing rollers while being conveyed to the next series of crushing rollers in the form of a compressed mass always maintained such state and could not be effectively sprinkled.

40 Moreover it has previously been very difficult to thoroughly saturate all parts of a layer of bagasse with water, for by machines hitherto in use the water has been usually showered only upon the upper surface of a layer of bagasse or supplied to both the upper and lower surfaces of the same. In the former case, that is when the water was showered only upon the upper surface of bagasse, the water could scarcely penetrate 45 the middle and lower parts of the layer of bagasse and in the latter case, that is, when water was supplied to both the upper and lower surfaces of the bagasse it would not

reach the middle part of the same in spite of the quantity of water absorbed by both 55 the upper and lower parts.

By the above mentioned process the water supplied was not always absorbed in a uniform condition by all parts of a layer of bagasse so that not only was the efficiency 60 of the saturation of the bagasse impaired but also the extraction of juice was greatly decreased.

The important object of this invention is to eliminate these defects, that is, to achieve 65 a uniform and complete mixing of the upper, middle and lower parts of a layer of bagasse with each other and at the same time to gain a uniform penetration of water even through the middle part of a layer of 70 bagasse so as to consequently permit of a high efficiency of juice extraction.

By this invention bagasse, which is sent forward from each series of milling rollers is effectively crushed and beaten by each 75 beater and simultaneously water is showered upon bagasse at two places, namely, at the front and rear parts of the said beater.

In the accompanying drawings, two series of crushing rollers (1) (2) (3) are provided 80 while a bagasse scraper (4) is attached to the upper milling roller (1) and another bagasse scraper (5) is attached to the rear milling roller (3). A beater (6) for the bagasse is provided the length of the same 85 being equal to that of the milling rollers, and is adapted to be rotated at a relatively high speed of about 500 revolutions per minute. The said bagasse beater is situated at the rear end of the scraper (5) while arranged 90 beneath the said beater and secured to the scraper (5) is a curved plate (7) of a length corresponding to that of the beater and scraper. Water supply pipes (8) are now provided and are perforated longitudinally 95 and are arranged above the beater and slightly in advance and rearwardly thereof so as to thoroughly saturate all of the bagasse, as it is being beaten. A curved covering and deflecting plate (9) is supported 100 over the foremost pipe section (8) and the beater (6) to prevent dispersion of the bagasse, which is pushed out backward from the rotating beater (6). The plate (9) terminates short of the rear pipe section (8) 105 so as not to interfere with the sprinkling of

- 2
- the beaten bagasse with water. In fact the curved end of the plate deflects the beaten bagasse to a point directly beneath the perforations in the rearmost pipe section (8). 5
- 5 A bagasse conveyor (10) is arranged one series of milling rollers and the next series of the same, and in this connection it is also to be noted that the beaten bagasse is directed thereon by the cover plate (9). 10
- 10 The construction of the rotating beater (6) is as follows: Several iron disks (11) as shown in Fig. 2, which have the desired thickness, are of equal diameter and are keyed to a common shaft 12 and in addition are each provided with three holes disposed at equal distances with respect to each other. 15

Between adjacent disks (11) there are inserted three steel beating heads (13) as shown in Fig. 2, having the desired length, width and thickness, and each has a hole of equal diameter to the holes on the disk (11). Through these aligning holes there are arranged three elongated bolt and nut 25 arrangements (14) (15) (16) as shown in Fig. 1 and Fig. 2 so as to hold the parts together as a unit.

The improved apparatus is set up, and as the beater is rotated, bagasse which have 30 been pushed out of milling rollers will be beaten and broken up by the said beater, whose speed is ten times that of the speed of bagasse after it has passed the end of the scraper (5). At the entrance and the exit 35 of the beater the bagasse absorbs the water uniformly and completely. After the mixing of the upper, middle and lower parts of the bagasse and the saturation of the same with water the bagasse falls down on 40 the bagasse conveyor (10) and is carried to the next series of milling rollers.

It is believed in view of the foregoing that a further detailed description of the invention is entirely unnecessary. Likewise 45 it is believed that the advantages will be appreciated.

Having thus fully described and ascertained the nature of my said invention what

is claimed as new and desired to be secured by Letters Patent is:

1. Improved means for beating and saturating bagasse comprising in combination milling means, conveying means situated rearwardly thereof, scraping means operatively associated with the milling means, beating means operatively arranged between the scraping means and conveying means, sprinkling means operatively arranged over the beating means and positioned slightly forwardly and rearwardly thereof to effect 60 thereon saturation of the bagasse at said points, and combined covering and deflecting means in operative relation with the sprinkling and beating means. 55

2. Improved means as claimed in claim 65 1, wherein the beating means includes a rotatable roller and connected to the rear of the scraping means and extending to the lower portion of the conveyor means and curved to form to the contour of the beater. 70

3. Improved means as claimed in claim 1, wherein the beating means includes a rotatable roller, a curved plate situated therebelow, and wherein the sprinkling means includes longitudinally perforated pipes for 75 sprinkling the bagasse as it enters and leaves the beater.

4. Improved means for beating and saturating bagasse comprising in combination, 80 milling means, beating means positioned rearwardly thereof, including a rotatable beating roller and a curved plate arranged beneath the roller and between which and the roller the bagasse is beaten after it leaves the milling means, a sprinkling means positioned above the beater and including longitudinally perforated pipe sections for saturating the bagasse as it enters and leaves the beating roller, and a curved covering and deflecting plate connected to one of the 85 pipe sections and arranged over said pipe section and the beater, substantially as and for the purposes set forth.

In testimony whereof I have affixed my signature.

HIROMU SEGUCHI.
